UNITED STATES PATENT OFFICE.

GEORGE H. PETERSON, OF BROOKLYN, NEW YORK, ASSIGNOR TO AMERICAN TELEPHONE AND TELEGRAPH COMPANY, A CORPORATION OF NEW YORK.

TELEPHONE-EXCHANGE SYSTEM.

Application filed June 18, 1925. Serial No. 38,058.

This invention relates to telephone exchange systems and particularly to circuits for establishing connections between mechanical and manual offices of such systems.

It has heretofore been the practice in establishing connections between a mechanical office of a step-by-step machine switching exchange and a manual office of such exchange to provide trunk circuits incoming from the full mechanical step-by-step office to the manual office, any one of which may be reached from any line in the full mechanical step-by-step office. By removing the receiver at the station associated with said line and dialing a predetermined digit or combination of digits known as the office code, the trunk circuit is selected and in turn is extended into connection with a preselected common circuit, known as a recorder and register circuit. Following the dialing of the code digits, the digits of the numerical portion of the wanted line number are dialed and recorded in the recorder and register circuit. After all the digit impulses required are received, the register circuit proceeds in combination with an indicating device such for example as disclosed in the Patent No. 1,572,679 issued Feb. 9, 1926, to Albert C. Powell, to display the number of the desired called line before an operator in the manual office, who thereupon completes a connection to the called line. Signaling follows automatically and when the called party answers the talking circuit is automatically established.

In small exchange areas it is possible to reach all offices of the area and all special service positions by dialing only one code digit thus setting a first selector. If the area embraces a rapidly expanding community or it is probable that adjoining exchange areas may in the future be joined to the original area, it is desirable to initially provide for access to a larger number of offices than are initially installed, the larger number of offices being reached by setting two selectors through the dialing of two office code digits. In this case it is desirable to instruct subscribers to dial two code digits as printed in the directory although only one of these digits may initially be required for setting switches. It therefore is necessary to dispose of one of the code digits dialed since it is not used to set a selector switch and if recorded at

the recorder of a manual office would cause the display of a wrong number before the operator.

The object of this invention is the provision of improved means to connect any line in a full mechanical step-by-step office to any desired line in a distant manual office.

A feature of this invention is the provision of means for recording impulses transmitted by a dial or impulse repeater, and whereby the first series of impulses dialed into the repeater is rendered ineffective or absorbed.

Another feature of this invention is the provision of a relay for absorbing the first series of impulses received whether it be the first one dialed or not.

Other features will appear from the detailed description.

Figure 1, in its upper left hand corner, shows a calling subscriber's station A in a full mechanical step-by-step machine switching system, a diagrammatic representation of the usual primary and secondary switches PLS and SLS, a first office selector S and a repeater R all located in the mechanical office X, and a trunk circuit extending to the manual office Y terminating in the plug P (Fig. 2) thereat. In the lower left portion of Fig. 1 is shown a recorder finder individual to the trunk circuit, having access to a plurality of recorders and registers, one of which is disclosed in Figs. 3 and 4. There are two recorder finders associated with each operator's position. The trunks at each position are divided in two groups, one half to the right of the operator and the other to the left. The trunks at the right hand group are associated with a finder such as 150, while a similar finder serves the left hand group. Conductor 135 shown in the lower left hand corner of Fig. 1 is used with the recorder finder serving the left hand group.

Fig. 2 shows the terminating end of the interoffice trunk disclosed in Fig. 1 and the line of a subscriber B terminating in the manual office Y.

Fig. 3 shows a recorder circuit and Fig. 4 shows a register circuit individual to the recorder circuit of Fig. 4.

To completely disclose the invention, Fig. 2 should be placed to the right of Fig. 1. Fig. 3 should be placed beneath Fig. 1 and

Fig. 4 should be placed to the right of Fig. 3.

In general, the system functions in the following manner:

A calling subscriber A, Fig. 1, in the full mechanical step-by-step office, desiring to communicate with a called subscriber B, Fig. 2, in a distant manual office, removes the receiver from the switchhook at station A and dials the desired number. Removing the receiver causes the primary and secondary line switches PLS and SLS, Fig. 1, to function and extend the calling line to the first or office selector S. The first digit in the series of digits dialed by the calling station is known as a code or office digit and causes the selector S to extend the calling line to an idle trunk circuit outgoing to the proper manual office. In series with this outgoing trunk circuit at the mechanical office, is a repeater R for receiving the impulses produced in the calling line circuit by the dial 100 and relaying them over the impulse circuit to a recording device associated with the trunk circuit selected in the distant manual central office. The recording device is equipped with suitable means for receiving the impulse transmitted by the repeater R, of recording them, and visibly displaying to the operator at the manual central office, by a suitable indicating means, the number of the desired called line. These indicating means are explained in detail in the above mentioned patent to Powell. The recording device is equipped with a means which absorbs the first digit received without registering it. The operator at the manual office Y then inserts the plug P of the trunk into the jack J of the called line and the called station B is automatically signaled. When the called station responds, the talking circuit is established and the conversation takes place. After the called number has been displayed before the operator in the manual central office, the recording and registering device, Figs. 3 and 4, having completed their functions, are released so as to render them available to other trunks in the group if required. When the conversation is finished and both stations disconnect, the manual operator at the central office Y receives a signal and removes the plug of the trunk circuit from the jack, thereby restoring the circuits to normal.

Having described the operation of the system in a general way, it is believed that its operation may be more clearly understood from a detailed description which follows.

When the receiver is removed from the switchhook at the calling station A, a circuit is closed including the calling station and the primary line switch PLS, extending the calling line to the secondary line switch SLS which in turn operates and extends the calling line to the first or office selector cir-

cuit S. The dial 100 is now operated and released and the selector S functions to select an idle trunk in the groups of trunks outgoing to the distant manual office Y. It will be assumed that the trunk shown in part in Fig. 1 is the one selected, in which case the calling line A is extended to the repeater R which operates and closes a bridge across the conductors 105 and 106 to operate the impulse relay 101 as follows: battery, through the left winding of relay 101, left back contact of relay 107, conductor 108, inner right back contact of relay 128, conductor 105, bridge circuit of repeater R, conductor 106, outer left back contact of relay 128, conductor 117, right back contact of relay 107 to ground through the right winding of relay 101. The windings 109 and 116 of the repeating coil are short-circuited at this time to prevent distortion of the impulses transmitted over the line to operate the impulse relay 101, hereinafter fully described. Relay 102 operates over an obvious circuit to ground on the front contact of relay 101. The operation of relay 102 closes a circuit for operating relay 103 as follows: battery, winding and back contact of the stepper 118 of finder switch 150, conductor 119, right winding of relay 103, conductor 120, brush and arc 115, conductor 121, outermost right back contact of relay 122, conductor 123, right back contact of relay 124, conductor 139 to ground on the left front contact of relay 102. Stepper 118 does not operate, due to the high resistance of relay 103 in series with it. Relays 104 and 301 now operate in series as follows: battery, through the winding of relay 301, conductor 131, fourth terminal and brush of arc 112, conductor 126, winding of relay 104 to ground on the inner right front contact of relay 103. Relay 302 now operates in an obvious circuit to ground on the outer right front contact of relay 301. Relay 103 in operating connects ground through its right front contact to brush 110, thereby grounding its fourth terminal which is multiplied over lead 130 to all other switches in the group, thereby making that terminal busy to all other switches.

The recorder finder switch 150 is arranged to pre-select an idle recorder circuit, hence all other recorder finder switches which may be resting upon the multiple terminals of this recorder circuit must now be stepped to the terminals associated with the next idle recorder circuit. This is accomplished as follows: Individual to each trunk circuit is a relay 127 which, whenever any trunk circuit is not in use, is connected to battery through the inner left contacts of a relay 122, also individual to such trunk, and through the right back contact of relay 103 of such trunk to brush 110 of the finder associated with such trunk. Assuming that

the brushes of some other recorder finder switches, corresponding to the brushes of finder 150 are resting upon the terminals corresponding to terminal 4 of the recorder 5 finder 150, parallel circuits through all corresponding relays 127 will be connected by way of the multiples to terminal 4 of arc and brush 110 to ground on the right front contact of relay 103 of the trunk circuit in 10 use. The various relays 127 will operate and close obvious local circuits to operate the various associated stepper magnets similar to 118, and in releasing will step their recorder finder switch brushes to the terminals 15 of the first recorder circuit in the group which is not busy. Whenever the recorder finder switch brushes come to rest upon the test terminal of an idle recorder circuit, the ground to hold relays 127 operated will be 20 removed and these relays will release, preventing the associated stepping magnets from rotating the switch brushes any further until the seizure of another trunk circuit necessitates the occurrence of this cycle 25 of operation. The operation of relays 103 and 104 extends the leads 133, and 134 through the brushes 113, and 114 for a purpose which will hereinafter be made apparent.

30 It has been observed that the recorder circuit is made busy when relay 103 operates. This immediate busy condition is intended to prevent the possibility of a double seizure of a recorder between the time 35 the brushes come to rest upon the terminals of a particular recorder and the time required to operate relay 302 which supplies ground to make the recorder circuit busy to all other recorder finder switches until the 40 recorder circuit has completed its functions as hereinafter described. After relays 103 and 104 have operated, the recorder is ready to receive impulses.

45 In accordance with this invention, it is required that the first digit received be absorbed and not form a part of the desired number. Therefore, when the dial 100 is operated by the calling station A for the last code digit the pulses will be absorbed as 50 will now be described. The dial 100 is operated and released and as it returns to normal it interrupts the circuit including the station loop and the repeater R, which in turn interrupts the circuit including the bridge of repeater R and relay 101. Relay 101 is a 55 fast operating relay and is designed to follow the impulses from repeater R. This impulse circuit operates relay 312 Fig. 3 upon each deenergization of relay 101 over 60 a circuit from ground, back contact of relay 101, outer left back contact of relay 122, right front contact of relay 102 conductor 137, right back contact of relay 211, conductor 214, outer left front contact of relay 65 103, brush 114, conductor 134, left back contact of relay 303, conductor 304, inner left back contact of relays 305, 306, 307, 308 and 309, inclusive, conductor 310, conductor 311 to battery through the winding of relay 312. Relay 312 operates in this circuit and 70 being slow to release remains energized until the pulses for this digit cease. Upon energizing it closes a circuit for operating relay 313 from ground on its front contact, through the right back contact of relay 313, conductor 314, inner left front contact of relay 301 to battery at the winding of relay 313. Relay 313 operates and locks to ground on its right front contact under control of relay 301 and places a shunt around relay 309, which may be traced from ground on the front contact of relay 312, conductor 315, resistance 316, left front contact of relay 313, conductor 317, outer left back contact and winding of relay 309, conductor 318 outer 80 left back contact of relay 305 to ground on the outer left front contact of relay 301. After the pulses for this digit have been received, relay 312 releases, and removes the shunt from around relay 309, allowing it 85 to operate in a circuit from ground on the outer left front contact of relay 301, conductor 318, winding and left outer back contact of relay 309, conductor 317, left front contact of relay 313, resistance 319, conductor 370 to battery through the outer right back contact of relay 305. Relay 309 operates and locks to battery on its outer left front contact.

90 The operation of relay 309 closes the pulsing circuit for the next digit which is the thousands digit from ground on the back contact of relay 101, outer left back contact of relay 122, right front contact of relay 102, conductor 137, right back contact of relay 211, conductor 214, left front contact of relay 103, brush and terminal of arc 114, conductor 134, left back contact of relay 303, conductor 304, to battery through the winding of relay 321 and in parallel therewith through the inner left back contacts of relays 305, 306, 307 and 308, inner left front contact of relay 309, conductor 320, normal contact and winding of magnet 406 of the thousands register TH, conductor 310, conductor 311 to battery through the winding of relay 312. Relay 321 operates to insure positive 100 stepping of magnet 406 regardless of the duration of each closure of the pulsing relay. The operation of relay 309 also closes a holding circuit for relay 321 extending from battery through the winding of relay 321, the inner left back contacts of relays 305, 306, 307, 308 and the inner left front contact of relay 309, conductor 320, back contact of magnet 406, conductor 407, right front contact of relay 309, right back contacts of relays 308, 307 and 306, inner right back contact of relay 305, right front contact of relay 321 to ground through the outer 105 110 115 120 125 130

right front contact of relay 301. Relay 321 is held operated in this circuit until the armature of magnet 406 is fully attracted and closes an auxiliary or booster circuit to insure the proper operation of stepping magnet 406 as follows: ground on the right outer front contact of relay 301, right front contact of relay 321, inner right back contact of relay 305, right back contacts of relays 306, 10 307 and 308 and right front contact of relay 309, conductor 407, through the winding of stepping magnet 406 to battery through the winding of relay 312. Stepping magnet 406 in operating, opens the holding circuit 15 through the relay 321 and when the impulse relay 101 reoperates and relay 321 releases, the circuit through stepping magnet 406 and the initial circuit of relay 321 are opened. Magnet 406 releases and on its 20 backward stroke rotates the brushes of register TH, one step in a counter-clockwise direction to the first terminal. With the brush associated with arc 405 resting upon the first terminal, a circuit is closed from ground 25 on the outer left front contact of relay 301, conductor 318, winding of relay 308, outer left back contact of relay 308, conductor 322, brush and No. 1 terminal of arc 405, conductor 371, resistance 319 conductor 370 to battery on the outer right back contact of 30 relay 305. The stepper 406 rotates the brushes of register TH step-by-step in this manner until the train of impulses produced by relay 101 ceases.

35 After the last impulse of the thousands digit of the impulse train ceases, relay 312 which energized in series with magnet 406 releases, removing the low resistance shunt 316 from around relay 308, which now operates and locks to battery over its outer left front contact. With relay 308 energized the impulsive and booster circuits are transferred at its right and inner left armatures, respectively, from the stepping magnet 406 40 of the thousands register switch TH to the stepping magnet 416 of the hundreds register switch H.

The digit corresponding to the hundreds digit of the desired number is now dialed 50 at station A and the stepping magnet 416 operates and rotates the H register switch which takes the proper setting in the same general manner as the thousands register switch. At the end of the impulse train relay 307 operates and locks in the same general manner as relay 309 and transfers the impulsive and booster circuits at its right and inner left armatures respectively, to the stepping magnet 426 of the tens register 55 switch. In like manner the tens digit is registered and relay 306 operates and locks and transfers the impulsive and booster circuits at its right and inner left armatures respectively, to the stepper magnet 436 of the 60 units register switch.

In like manner the units digit is registered and upon the completion of the registration of this digit and the release of relay 312 a circuit is closed for relays 303 and 305 in parallel which may be traced from ground 70 on the back contact of relay 312, conductor 324, brush and arc 435, conductor 427 to battery through the operating winding of relay 303 and also through the right winding of relay 305. The operation of relay 305 releases relays 306, 307, 308 and 309 as they have no further functions to perform at this time. The operation of relay 303 disconnects at its outer right and outer left back contacts the pulsing leads from the 75 trunk in order to prevent any false operation of the recorder selector switches. Relay 303 also furnishes battery to light the associated trunk assignment lamp 201 over a circuit from battery through its inner 80 right front contact, right winding, conductor 133, arc and brush 113, inner right front contact of relay 104, conductor 138, assignment lamp 201, outer right back contact of relay 205, conductor 215 to ground 85 at the outer right back contact of relay 203. The operator, upon noticing the lighted assignment lamp 201 operates the assignment key 216 which operates relay 203 over a circuit from ground on the left front contact 90 of relay 102, conductor 139, inner left back contact of relay 209, conductors 217 and 218, upper contact of key 216 to battery through the right winding of relay 203. The operation of assignment key 216 also operates the 100 indicator in the peg count circuit through the lower make contact of the key thereby registering the initiation of the call. Relay 203 upon operating closes a holding circuit 105 for itself independent of key 216 from battery through both of its windings and inner left contact, thence to ground at the left contact of relay 102 as previously traced, and closes a circuit for holding relay 103 from ground on the outer left front contact of relay 203, conductor 212, left front contact of relay 104 to battery through the left winding of relay 103, thereby preventing its release when the circuit through its right winding is opened due to the later operation of relay 122. Relay 203 also closes a circuit for operating relays 122 and 128 in parallel from ground on its inner right front contact, conductor 213, to battery through the winding of relay 122 and to 110 battery through the winding of relay 128. Relays 128 and 122 lock over the inner left front contact of relay 128 to ground at the left contact of relay 102.

At this time relay 323 operates over a circuit from battery through its winding, conductor 132, arc and brush 111, conductor 212 to ground on the outer left front contact of relay 203, connecting ground through its multiplied right contacts to arcs 401, 411, 115 120 130

421 and 431 of the registers, thereby lighting the lamps in the position indicator associated therewith as explained in the patent to A. C. Powell, above mentioned. Relay 5 203 also disconnects steady ground from lamp 201 and connects interrupted ground through interrupter 204, outer right front contact of relay 203, conductor 215, outer right back contact of relay 205 through 10 lamp 201, conductor 138, inner right front contact of relay 104, brush and arc 113, conductor 133, right winding of relay 303 to battery on the right front contact of relay 303 thereby flashing the assignment 15 lamp 201 as an indication to the operator that the call on the trunk has been indicated on her lamp indicator.

Relay 128 upon operating removes the shunt from around the windings 109 and 20 116 of the repeating coil thereby preparing the trunk for talking transmission, the repeating coil being shunted out of the circuit during pulsing to improve pulsing conditions. Relay 122 operated, disconnects 25 the pulsing lead from the back contact of relay 101 thereby preventing any false operation from taking effect after assignment key 216 has been operated. The operation of relay 122 opens the circuit of 30 relay 127 by disconnecting battery from its operating circuit at the inner left back contact of relay 122, and at its outer right back contact opens the circuit through the right winding of relay 103, but relay 103 does not 35 release at this time as it is held operated through its left winding to ground on relay 203. Relay 122 also closes in part a circuit from battery through the disconnect lamp 210, right back contact of relay 209, conductor 219, inner right front contact of relay 122, which is now open at the outer right 40 contact of relay 104.

Upon the operator's ascertaining the number desired, from the call indicator, she inserts plug P in the jack J of the desired line. 45 Upon the insertion of plug P into jack J, a circuit is closed from ground through relay 221, sleeve of the jack and plug, conductor 222 to battery through relay 209. Relay 50 209 operated, closes the talking conductors 140 and 150 to conductor 144 and thence through the subscriber's station B. Relay 209 operated, also operates relay 207 over a circuit from ground on its inner right front 55 contact, conductor 224, left back contact of relay 208, right back contact of relay 206, through the winding of relay 207, conductor 225, outer right front contact of relay 128, conductor 143 to battery thereby operating 60 relay 207. The operation of relay 209 also opens the circuit through relay 203, releasing it. Relay 207 operated opens the talking leads 140 and 141, and connects ringing lead 227 and ground to conductors 150 and 151 65 to ring the called subscriber B. Relay 203 released releases relay 323 in the recorder circuit, thus extinguishing the call indicator lamps. The release of relay 203 also releases relay 103 which in turn releases relay 104. The release of relays 103 and 104 opens 70 all leads between the trunk and associated recorder circuit. At this time the register and recorder circuits are released as described in the patent to A. C. Powell by the operation of relay 346 which operates upon 75 the release of relay 301. The winding of relay 207 being connected in parallel with lamp 210 prevents the lamp from lighting but allows the relays to operate. When the called subscriber answers by removing the 80 receiver from the switchhook, relay 208 operates in series with the subscriber's set. Relay 208 operated, removes the shunt from around relay 206 allowing it to operate in series with relay 207. Relay 206 operated, 85 locks under control of relay 209 over a circuit from ground on the right front contact of relay 209, conductor 224, winding and front contact of relay 206, conductor 225, outer right front contact of relay 128, conductor 90 143 to battery and short circuits relay 207 through its front contact, thereby releasing it. The release of relay 207 disconnects ringing current from conductors 150 and 151 and connects these conductors to conductors 140 and 141 and thence to the repeating coil. 95 Lamp 210 is now shunted by relay 206, preventing it from lighting until the calling subscriber replaces the receiver on the 100 switchhook.

Relay 136 operates at this time over a circuit from battery, winding 142 of the repeating coil through the winding of relay 136, conductor 141 left back contact of relay 207, conductor 151 through plug P, jack J and the subscriber's set, conductor 144, outer left front contact of relay 209, conductor 150, right back contact of relay 207, conductor 140, winding 145 of the repeating coil to ground. The operation of relay 136 closes a 105 circuit for operating relay 107 from battery through its winding, front contact of relay 136, conductor 213 inner left front contact of relay 128, to ground on the left front contact of relay 102. The operation of relay 107 reverses battery over leads 108 and 117 through its contact for the purpose of 110 registering the call at the distant end of the trunk.

When the receiver at calling station A is 115 replaced on the switchhook, the relay 101 releases in turn releasing relay 102 which opens the holding circuit for relays 128 and 122. The release of relay 128 opens the holding circuit hereinbefore traced for relay 206, and removes the shunt which was traced 120 through its right outer front contact from around disconnect lamp 210, allowing it to 125 light over an obvious circuit from battery through lamp 210 to the right front con- 130

6 tact of relay 209. The operator, upon receiving this disconnect signal, withdraws the plug of the cord P from jack J thereby opening circuits of the operated relays allowing them to release and restore the circuit to normal.

Relays 205 and 211, are used with key 202 for work at adjacent right and left operator's positions. Relays 344 and 345 in conjunction with register arcs 400, 410, 420, 430, 402, 412, 422 and 432 are also used for indicating at the right and left adjacent positions. The operation of these relays and registers have been fully described in the patent to A. C. Powell and as these pieces of apparatus are not essential to an understanding of the present invention a description thereof will not be given herein.

What is claimed is:

- 23 1. In a telephone system, an originating office, a calling line terminating therein, a calling device associated therewith, a terminating office, called lines terminating therein, means for establishing a connection between said offices, an operator's position in said latter office, a call indicating device at said operator's position, said indicating device having a plurality of registers for registering digits of called line numbers transmitted thereto by said calling device, and means in said indicating device for absorbing without registering the impulses correspondingly to one of the first digits transmitted by said calling device.
- 25 2. In a telephone system, an originating office, a calling line terminating therein, a calling device associated therewith, a terminating office, called lines terminating therein, means for establishing a connection between said offices, an operator's position in said latter office, a call indicating device at said operator's position, said indicating device having a plurality of registers for registering digits of called line numbers transmitted thereto by said calling device, and a relay in said indicating device for absorbing the impulses corresponding to one of the first digits transmitted by said calling device.
- 27 3. In a telephone system, an originating office, a calling line terminating therein, a calling device associated therewith, a terminating office, called lines terminating therein, means for establishing a connection between said offices, an operator's position in said latter office, a call indicating device at said operator's position, said indicating device having a plurality of registers for registering digits of called line numbers transmitted thereto by said calling device, and means in said indicating device for absorb-

ing without registering the impulses corresponding to the first digit transmitted to said indicating device by said calling device.

4. In a telephone system, an originating office, a terminating office, called lines terminating in said latter office, means for establishing a connection between said offices, an operator's position in said latter office, a call indicating device at said operator's position, said indicating device having a plurality of 70 registers for registering digits of called line numbers, means in said originating office for transmitting series of impulses corresponding to digits of called line numbers for setting said registers, and means in said indicating device for absorbing without registering one of the first of such series of impulses. 75

5. In a telephone system, an originating office, a terminating office, called lines terminating in said latter office, means in said originating office for transmitting series of impulses corresponding to the office code and numerical designations of called lines, automatic switching mechanism responsive to certain of said series of office code impulses 80 for establishing a connection between said offices, an operator's position on said terminating office, a call indicating device at said position having a plurality of registers for registering the numerical designations of 85 called lines in accordance with series of impulses transmitted thereto from said originating office, and means, in said indicating device for absorbing the last of said series of code impulses without registration thereof. 90

6. In a telephone system, an originating office, a terminating office, means for establishing a connection between said offices, means in said first office for transmitting series of impulses to said second office, means in said second office for registering impulses transmitted to said second office, and means at said second office for absorbing one of the first of said series of impulses. 100 105

7. In a telephone system, an originating office, a terminating office, means for establishing a connection between said offices, means in said first office for transmitting series of impulses to said second office, means in said second office for registering impulses transmitted to said second office, and means at said second office for absorbing the first one of the series of impulses received at said second office. 110 115

In testimony whereof, I have signed my name to this specification this 16th day of June 1925.

GEORGE H. PETERSON.
